UNITED STATES PATENT OFFICE.

NEVA-RAE RUSSELL, OF UNIVERSITY PLACE, NEBRASKA.

GAME-CARDS.

1,234,393.

Specification of Letters Patent. Patented July 24, 1917.

Application filed December 16, 1915. Serial No. 67,187.

To all whom it may concern:

Be it known that I, NEVA-RAE RUSSELL, a citizen of the United States, residing at University Place, in the county of Lancaster and State of Nebraska, have invented certain new and useful Improvements in Game-Cards, of which the following is a specification.

My invention relates to games and has for 10 its object to provide a new and interesting as well as instructive card game.

The invention consists of a plurality of 15 series of suit cards bearing designations indicating a certain city and the number of miles traveled by the player in reaching that place, each card also bearing a designation peculiar to all the cards of the different suits or series and a plurality of honor cards bearing designations distinguishing them 20 from each other and from the suit cards and all of the cards being designed to be included in a single pack adapted to be shuffled and dealt to players.

In the accompanying drawings:

25 Figures 1, 2, 3, 4 and 5 are plan views of all the cards of a series or suit.

Figs. 6, 7 and 8 are plan views of a single card of each of the other three series or suits and

30 Figs. 9, 10, 11 and 12 are plan views of the honor cards.

Referring more specifically to the drawings in which like reference numerals designate corresponding parts throughout 35 the several views, 5 designates a series of five suit cards 6, 7, 8, 9 and 10 respectively, each of which bears a common distinguishing mark which, in the present embodiment is an airship 11. These five cards each bear 40 the name of a city as at 12 and are numbered consecutively from 1 to 5 which numbers represent the number of miles a player is supposed to travel in going from base 45 (not indicated) to the city designated on the card.

There are four series of suit cards of five cards to a series, the cards of one series differing from the corresponding cards of each of the other series only in the name of the 50 city which it bears. For instance, in Fig. 6 the card 6' bears the designation Blue City as at 12'; in Fig. 7 the card 7', bearing the designation Black Hill and in Fig.

8, the card 8' bears the designation Brownville. The other four cards (not shown) of 55 each of these three series are numbered 2 miles, 3 miles, 4 miles, and 5 miles, respectively, but otherwise are identical with their respective series card just described.

The four trump cards 11, 12, 13 and 14 60 illustrated in Figs. 9, 10, 11 and 12 are counter or honor cards. They each bear a designation distinguishing them one from the other and from the suit cards as at 11', 12', 13' and 14' labeled an air ship, Zeppelin, biplane and triplane, respectively. The value of and the manner in which the various cards are to be played will be apparent from the following brief description of play. 70

The players sitting opposite are partners, work for each other's interest and have a common score. After cards are dealt one at a time, each player has the privilege of naming "trumps." The suit named 75 "trumps" becomes superior in value to the other suits, so that the highest card of a trump suit can take any card in all other suits, and can only be taken by a lower card of its own suit. The highest bidder selects 80 a trump and plays it face up on the table. The play passes to the left each player playing a card of the same suit as the one lead if he holds one, if not any card the player chooses. The player placing the 85 card of the lowest value takes the four cards which are called a trick.

If the bidder fails to make the points he bids he is said to be "down" and it is counted against his score. If cards were 90 all played to the best advantage then the score would be eleven. The six tricks would count six. The Zeppelin if it took a trick one. Airship—two. Biplane if it took a trick one; triplane if it took a trick one. 95 The total would be eleven.

The four counter cards if properly played count more than the others. For instance the airship is known as the "joker" card. It has power to take any trick in 100 which it appears. It can take a trump, or may be used as a trump if player so desires. It counts two points beside the trick which it takes. Another counter is the Zeppelin which counts one, and it takes any trick that 105 does not contain a trump. Still another

counter is the biplane which takes any trick (without a trump) that contains a two, and it counts one. Triplane takes any trick (without a trump) that contains a three and 5 counts one.

Having thus described my invention:
What I claim is:

- 10 1. A pack of game cards comprising a plurality of different suits, each card of a suit bearing a numerical and a geographical designation indicating a distance traveled and a point reached respectively, and a plurality of honor cards bearing designations distinguishing them one from the other.
- 15 2. A deck of cards comprising a plurality of different suits, the cards of each suit being distinguished from the cards of the other suits by a different geographical designation thereon, and a plurality of honor 20 cards having representations of aeronautical

cal devices thereon, each of said honor cards having an aeronautical device different from the other said honor cards for a purpose specified.

3. A deck of cards comprising a plurality of different suits, the cards of each suit being distinguished from the cards of the other suits by a geographical designation thereon, the cards of each suit being numbered serially, and a plurality of honor 30 cards having representations of aeronautical devices thereon, each honor card having an aeronautical device different from the other said honor cards, and each said aeronautical device having a different relative 35 value from the others for a purpose specified.

In testimony whereof I affix my signature hereto.

NEVA-RAE RUSSELL.
